DESIGN FOR A BILLFOLD

William A. Pence, Adell, Wis., assignor to Enger-Kress Company, West Bend, Wis., a corporation of Wisconsin

Application March 26, 1945, Serial No. 118,705

Term of patent 14 years

(Cl. D87—3)

To all whom it may concern:

Be it known that I, William A. Pence, a citizen of the United States, residing at Adell, in the county of Sheboygan and State of Wisconsin, have invented a new, original, and ornamental Design for a Billfold, of which the following is a specification, reference being had to the accompanying drawing, forming part thereof.

In the drawing:

I claim:
The ornamental design for a billfold, as shown

WILLIAM A. PENCE.
